LAWRENCE A. HYLAND, OF WASHINGTON, DISTRICT OF COLUMBIA

RADIO TRANSMITTER

Application filed January 15, 1932. Serial No. 586,909.

(GRANTED UNDER THE ACT OF MARCH 3, 1883, AS AMENDED APRIL 30, 1928; 370 O. G. 757)

This invention relates to a radio transmitter and more particularly to a radio transmitter for use on board aircraft, in which an oscillator and one or more stages of radio frequency amplification is used for regular transmission and the oscillator alone, or with a limited number of stages of amplification, is used for emergency transmission.

In providing aircraft communication systems there is a major problem involved in assuring emergency communication. At the present time it is the practice to use engine-driven generators as the source of power. In an emergency, when a forced landing is necessary, wind-driven generators and the engine-driven generators are usually stopped. To effect emergency communication on single engine ships it has been the practice to include in the aircraft communication equipment a small emergency transmitter including a hand-operated generator or small batteries. This equipment has been limited to extremely small powers and could be operated for only a short period of time. In many cases no emergency equipment has been carried whatever, reliance having been placed on the main transmitter during the period that the craft was in the air and trusting that, in the interval between notification that a landing was necessary and the actual landing, it would be possible to send out very brief emergency signals. The system disclosed herein will make emergency communication with considerable power readily feasible and since the equipment used for emergency purposes is an integral part of the main equipment, the device will always be ready in the event of an emergency.

The principal object of this invention is to provide an aircraft radio transmitter normally fed with the necessary operating potentials by a generator or generators driven from the prime mover that drives the craft, or wind-driven generators with means for supplying necessary operating potentials to a portion of the transmitter when the primary generators are rendered inoperative.

Another object of this invention is to provide a means for storing energy derived from the primary generators in such a form that

it may be utilized to drive the emergency equipment, together with a means for automatically disconnecting the primary generators from the storing means when the primary sources become inoperative to produce a sufficient potential to charge said storing means.

Other and further objects of this invention will be made apparent from the following description and the accompanying drawing wherein the single figure shows a schematic circuit diagram of one embodiment of this invention.

Referring now to the drawing, reference number 1 denotes a combination low voltage and high voltage direct current generator such as is ordinarily employed on aircraft and which has a common field winding. 2 is a voltage regulator of the Terrel type which provides for the control of the generator voltage through the action of the contacts in cutting a resistance into and out of the field circuit of the generator as the voltage changes. 3 is a reverse current relay which is employed in a low voltage circuit for connecting the low voltage winding of the generator 1 to the storage battery 4 when the generator has developed the required potential. 5 is a dynamotor which is driven from battery 4 and supplies through its high voltage winding the necessary plate potential to operate the electron tube oscillator 6. An electron tube amplifier is shown at 7. The filaments of the tube in both the oscillator and the amplifier are heated normally from the low voltage winding 17 of the generator 1. The plate circuit of the oscillator 6 is fed from the high voltage winding 21 of the dynamotor 5. The plate circuit of the amplifier 7 is fed from the high voltage winding 15 of the generator 1.

Under normal conditions of operation, that is, when no emergency exists and the armature of generator 1 is being driven at proper speed to generate the required filament and plate potentials, the switch 9 is closed to position "b", in which case the output circuit of the oscillator 6 is connected to the input of the amplifier 7 and the output of said amplifier is connected to the radiating

system comprising ground 8 and antenna 10. In this condition, the transmitter is operating at its normal output. Assuming now that an emergency exists, in which case the motor 5 or other source of power normally operating generator 1 ceases to function, the reverse current relay 3 opens a point in the circuit between the said generator and battery 4 and dynamotor 5 continues to be driven, being 10 supplied with the necessary operating potential from storage battery 4, which has been floating across the low voltage winding of generator 1. The high voltage winding therefore supplies the proper potential for 15 the plate circuit of the oscillator 6. The switch 9 is then closed to position "a", in which case the oscillations of the oscillator 6 are transmitted by the conductor 11 to the antenna 10, from which they are radiated.

20 In the drawing, oscillator 6 is shown in a more or less conventional form and it is to be understood that other arrangements employing this oscillator circuit or its equivalent together with circuits for keying or modulating with voice frequencies may be used instead, either alone or in combination with a stage or stages of amplification before being connected to either the antenna directly or to the amplifier 7. The amplifier 7 is 25 shown as a single stage, however, several stages may be used, in which case the principal of operation of the system would remain the same.

The voltage regulator 2 which is used to 30 automatically control the output potentials of both the low and high voltage windings of generator 1 consists of a relay winding 12 connected across the low voltage terminals of the generator which is adapted to actuate 35 armature 13 to open a path of low resistance in shunt with resistance 14 in the field winding circuit to reduce the field excitation as the potential increases. Obviously any type of voltage regulator performing the function of 40 reducing the field excitation with an increase in the output voltage may be employed.

The reverse current relay 3 is shown as a relay having two windings, one of which is connected across the low voltage leads from 45 generator 1 and the other of which is connected in series with the generator 1 and the battery 4 upon the initial attraction of armature 18 by the first winding. Obviously any type of reverse current relay, that would 50 connect the low voltage output of generator 1 to the battery 4 when sufficient potential existed at the output terminals of said generator and which would open the circuit to said battery and prevent the reverse current 55 flow from said battery back to the generator when the generator is not delivering sufficient potential to charge said battery, could be used.

It will be understood that the above description and accompanying drawing com-

prehend only the general and preferred embodiment of my invention, and that various changes in construction, proportion and arrangement of parts may be made within the scope of the appended claims, without sacrificing any of the advantages of my invention. 70

The herein described invention may be manufactured and used by or for the Government of the United States for governmental purposes without the payment of any 75 royalty thereon.

I claim:

1. In combination, a power-driven generator having low potential and high potential windings, a storage battery, means for connecting the low potential winding of said generator to said battery responsive to the generation of a predetermined potential by said generator, a dynamotor having a high voltage winding, means connecting said dynamotor to be driven by said battery, an electron tube oscillator, means connecting the high voltage winding of said dynamotor in the plate circuit of said electron tube oscillator, means connecting said battery in the filament circuit of said electron tube oscillator, a radio frequency amplifier, means connecting the high voltage winding of said power driven generator in the plate circuit of said amplifier, means connecting said battery in the filament circuit of said amplifier, a radiating system, and means for selectively connecting said radiating system to the output circuit of said amplifier or said oscillator whereby said radiating system may be energized by said amplifier when said power driven generator is functioning or by said oscillator when said generator is not functioning. 100

2. In combination, a power-driven generator having a plurality of output windings, automatic means for regulating the output potential of all of said windings, a storage battery, means for connecting one of said windings to said battery responsive to the generation of a predetermined potential thereby, a dynamotor provided with a high voltage output winding, an electron tube oscillator, means for connecting the output winding of said dynamotor in the plate circuit of said electron tube oscillator, an electron tube amplifier, means for connecting said battery to energize the filaments of the tubes in said oscillator and said amplifier, means for connecting one of the output windings of said power-driven generator in the plate circuit of said amplifier, a radiating system, means for connecting the output of said oscillator to the input of said amplifier, and means for selectively connecting said radiating system to the output of said amplifier or said oscillator. 115

3. In an aircraft radio transmitting system, a power-driven generator, a battery, a dynamotor, an electron tube oscillator, an amplifier, means for normally driving said dy- 120

130

namotor comprising said generator with said battery floating thereacross, means for driving said dynamotor from said battery and disconnecting said generator from said battery when said generator is inoperative, means for supplying plate potential to said oscillator comprising said dynamotor, means for supplying plate potential to said amplifier comprising a high potential winding of said power-driven generator, means for supplying filament current to said oscillator and said amplifier comprising the same means as that used to drive said dynamotor, whereby said oscillator and said amplifier may be energized when said power-driven generator is functioning and said oscillator may be energized when said power-driven generator is not functioning.
